Primary Examiner — Paula Allen Greene

(57) **CLAIM**

The ornamental design for a headset, as shown an described.

DESCRIPTION

FIG. 1 is a perspective view of a headset showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view thereof;

FIG. 9 is a perspective view of the headset showing earbuds being pulled out; and,

FIG. 10 is a perspective view of the headset showing hinges being folded.

1 Claim, 8 Drawing Sheets(56)
